CURTAIN SUPPORT FOR ARTICLES OF
FURNITURE

Annette E. Fridolph, New York, N. Y.

Application December 9, 1946, Serial No. 715,083

2 Claims. (CL 311—2)

1

This invention relates to improvements in furniture and particularly to improved means for attaching decorative hangings, such as, draperies, curtains, skirts and the like to furniture. This application is a continuation-in-part of my co-pending application Serial #448,405, filed June 25, 1942, now Patent No. 2,416,608.

It is an object of the present invention to provide a concealed traverse member, as an integral part of an article of furniture, for slidably supporting decorative hangings, panels and the like, thereby avoiding the use of auxiliary curtain or drapery rods, or hangers.

Another object of the present invention is to provide an improved article of furniture such as a table or counter having a top with an overhanging edge and which is so arranged that a sliding curtain may be suspended invisibly beneath such edge. The invention provides an improved curtain suspension which may be used on articles of furniture such as vanity tables, kitchen work counters, desks, book cases, china closets and the like in an attractive and inexpensive manner and so constructed as to operate efficiently and smoothly and with minimum of trouble.

For a better understanding of the present invention, reference may be had to the accompanying drawings in which:

Figure 1 is a fragmentary cross sectional view of an edge of a table top provided with one form of the present invention;

Figure 2 is a similar view illustrating a modified form of construction;

Figure 3 is a perspective view of a vanity table incorporating the present invention;

Figure 4 is a fragmentary sectional view of a table top edge incorporating another form of the present invention;

Figure 5 is a similar view illustrating a further modified form;

Figure 6 is a perspective view partly broken away illustrating the invention applied to a table top cabinet;

Figure 7 is a perspective view of a bed incorporating the present invention wherein the side panels are so formed as to provide a traverse slot for receiving decorative hangings and the back of the head of the bed is also provided with a traverse slot for receiving a decorative panel; and

Figure 8 is a partially cutaway perspective view showing a couch or piece of similar furniture incorporating the present invention.

Referring now to the drawing and particularly to Figure 1, there is illustrated a portion of a table top 10, the outer edge thereof being indicated at 55

12. Rabbeted to its lower surface is a depending flange or valance 14 which is preferably arranged flush with the outer edge 12. Formed in the lower horizontal surface of the top 10 behind the valance board 14 is a T-shaped slot or channel 16. The shape of the slot or channel 16 may be varied so long as it is generally similar to a key-hole in that it is provided with a narrow mouth or slit 18 and an enlarged recess 20 beyond the mouth. 5 Slidable in the slot 16 are a plurality of slider elements 22 having enlarged heads 24 freely movable in the recess 20 and flexible tape portions 26 extending through the slit 18. These slider members may have their heads 24 covered with fabric to facilitate ease of sliding the curtain in the groove. A curtain 28 is suspended from the sliders 22 and may have slider members individually sewed thereto. Alternatively the sliders may first be sewed onto a tape at uniform intervals, which 10 tape is subsequently sewed to the curtain 28. The general appearance of a vanity table thus constructed is seen in Figure 3 from which it is apparent that the upper hem of the curtain is concealed behind the valance board 14. 15 20 25 At one point in the groove, slot or channel 16 there is provided an aperture 30 (Figure 6) which is a lateral enlargement of slit 18 of a width approximately the width of the recess 20. This aperture permits the sliders to be inserted in the 30 groove one at a time by bending the flexible tape 26 to introduce the heads 24 angularly into the recess 20. The aperture 30, however, is shorter than the sliders 24 to permit them to pass across it after they have once been inserted in the slot 35 40 45 50 55 60 65 70 75 80 85 90 95 100 105 110 115 120 125 The action of the fabric covered heads 24 sliding in a groove or channel in the wood or similar material is extremely smooth and the flexibility of the tapes 26 materially assists in this action. Thus the curtain may be slid back and forth along the groove easily without the possibility of jamming or sticking.

The provision of the aperture 30 enables the curtain to be readily applied or removed and inasmuch as the slider members 22 are washable, they need not be detached from the curtain when it requires laundering. It is thus apparent that the present invention provides an improved means for hanging a sliding curtain or skirt beneath the edge of a table without the addition of any separate, exposed parts.

Where the edge of the table or the edge of an ornamental side board 60 of a bed is exposed, as shown in Fig. 7, the slot may be concealed in a different way. The slider members 22' are sewed to a continuous length of tape 61, the tape being sewed to the skirt or curtain 28' so that the top edge of the curtain is about even with or slightly above the upper ends of the sliders. When the sliders are inserted into the slot 16' 20 formed in the ornamental surface, the slot is concealed by the top edge of the curtain or skirt. The skirt 28' can be attached to the side board 60 by inserting the sliders successively into the aperture 30' in the slot until all of them are 30 engaged in the slot.

In applying an ornamental covering to the headboard 62 of a bed, the headboard of the bed is provided with a T-shaped slot 16" near the top of its rear surface as shown in Fig. 7. The slot 16" has an aperture 30" therein near one end to receive the slider members on the top edge of the ornamental panel 63.

The ornamental panel 63 can be attached to the headboard 62 in the same way that the skirt 28' is attached to the side board 60.

If it is desired to remove the skirt or the ornamental panel from the bed for washing or cleaning, it is only necessary to grasp the skirt or panel and tilt the end slider slightly to slide the same through the aperture. The succeeding slider members can be tilted and withdrawn through the aperture and the skirt or panel thereby removed easily. The slider members being of cloth and small in size can be washed or cleaned with the hanging.

In Fig. 8 is shown the invention as applied to a lounge or piece of porch furniture 64. In this lounge, a slot 65 is formed near the top of the rear surface of the back member 66 of the lounge. A similar slot 67 is formed in the front surface of the back member 66 near its lower edge and preferably behind the seat of the lounge. The ornamental covering 68 for the back of the lounge has slider members at its top and bottom edges for insertion into the slots 65 and 67. The apertures (not shown) for inserting the sliders into the slots 65 and 67 may be at one end of the slots or at any convenient location along the slots.

From the preceding description of typical forms of the invention, it will be apparent that I have provided a most convenient and inconspicuous

traverse and supporting means whereby skirts, draperies, curtains and the like can be easily attached to and detached from various articles of furniture and that these articles present unmarred and attractive exposed surface portions even in the absence of such curtain, drapes or skirts because the supporting tracks are concealed within the furniture.

It will be understood that the invention is applicable to other types of furniture than those disclosed and described herein and that the dimensions of the sliders of the tracks therefore may be modified in accordance with the requirements. Therefore, the forms of the invention disclosed herein should be considered as illustrative and not as limiting the scope of the following claims.

I claim:

1. An article of furniture such as a table, counter or the like, comprising a member having a normally visible outer surface extending to a peripheral edge portion and an inner normally concealed surface within said peripheral edge portion, and a channel of small transverse dimensions formed integrally in the concealed surface of said member, said channel being composed of a longitudinal recess within said member and a relatively narrow slit opening from said recess through and along said inner concealed surface to receive slidably a thin body portion of a curtain-supporting slider element having an elongated enlarged head movable freely in said recess, so that the furniture article itself contains integral and normally concealed means in said member for slidably draping its understructures.

2. An article of furniture as described in claim 1, said slit having a lateral enlargement at a convenient point forming a passageway for movement of such slider element into and from said channel.

ANNETTE E. FRIDOLPH.
